UNITED STATES PATENT OFFICE.

JAMES T. HALL, OF COALINGA, CALIFORNIA, ASSIGNOR TO BUNTING IRON WORKS, OF COALINGA, CALIFORNIA, A CORPORATION OF CALIFORNIA.

COMBINED CALF-WHEEL AND DRIVE MEMBER.

1,108,576.

Specification of Letters Patent.

Patented Aug. 25, 1914.

Application filed December 9, 1911. Serial No. 664,715.

To all whom it may concern:

Be it known that I, JAMES T. HALL, a citizen of the United States, residing at Coalinga, in the county of Fresno and State of California, have invented certain new and useful Improvements in Combined Calf-Wheels and Drive Members, of which the following is a specification.

The hereinafter described invention relates to a combined calf wheel and drive member for use in connection with oil derricks in the work of sinking oil wells; the object of the invention being the production of a calf wheel which shall have free rotation on its fixed sustaining shaft, whereby binding of the same is overcome in case of the shaft getting out of true alinement with its bearing by reason of an uneven sagging or settling of the frame timbers supporting the same.

To comprehend the invention reference should be had to the accompanying drawings, wherein—

Figure 1 is a perspective view of the improved wheel held to the frame pieces of an oil derrick. Fig. 2 is a longitudinal sectional view of the improved wheel, disclosing the same rotatably mounted on its sustaining shaft, and the said shaft secured to the frame pieces of the oil derrick. Fig. 3 is a detail view illustrating the manner of securing the sustaining shaft to the frame pieces of the derrick.

In the drawings, the numeral 1 is used to designate a metallic cylindrical shell on which the calf line cable is wound, and 2 a sustaining shaft for the said shell. This shell is formed on its inner surface with a series of radial disposed lugs, projections or ribs 3, which bear onto the surface of the sustaining shaft 2 and serve to strengthen the cylindrical shell to prevent the crushing thereof under the compression strains to which the same is subjected by the winding of a cable thereon, thereby enabling a much lighter shell to be used than otherwise could be successively employed.

The shell or hollow drum 1 is secured at its ends to the bearing hubs 4 and 4', each of said hubs being provided with a circumferentially projecting flange wall 5. Inasmuch as the driving strains fall onto the bearing hub 4, which constitutes the drive end of the calf wheel, the inner end thereof is secured to the shell or drum 1 by four or

more radially disposed securing pins 6 and a square longitudinally disposed key 5', while the inner end of the bearing hub 4' is secured to the opposite end of the shell or drum by two radially disposed securing pins 6'. However, the number of securing pins used at either end may be varied as desired, this being an immaterial constructive feature. The square key connection 5' removes the shearing strains from the securing pins 6.

The ends of the shell or drum 1 are formed somewhat heavier than the main body thereof, as shown at 7, and provided with a series of projecting shoulder portions, which bear onto the bearing hubs 4 and 4'. Each bearing hub 4 and 4' is provided with a bronze bushing 8, which bear onto the shaft 2 and serve as an inner removable wear surface for the bearing hubs, the required lubricant being admitted to the shaft 2 through the pipe tap bores 9 in the bearing hubs 4 and 4' and the bushing or lining 8.

The formed winding shell or drum 1 is loosely mounted on the sustaining shaft 2, and held thereon against endwise movement by means of the end lock collars 10 slipped onto each end of the said shaft and held thereto by the set screws 11, the longitudinal position of the shell or drum relative to the shaft 2 being varied by adjusting the position of the lock collars 10 on the said shaft.

The sustaining shaft 2 is secured against rotation within the bearing boxes 12, attached to the frame uprights 13, by means of the stirrup bolts 14, which embrace the ends of the shaft and pass through the bearing plates 12 and frame uprights 13, and are drawn tight by the tightening nuts 15 screwing onto the threaded ends thereof. These bolts embracing the ends of the sustaining shaft 2 secure the same securely within the seat of the bearing plates or supports 12 and hold the shaft against rotation.

The drum or shell 1 being loosely supported on the sustaining shaft and free to rotate thereon without transmitting its movement of rotation to the said shaft, there is no tendency for the rotatable drum or shell to bind in any manner in case of the supporting frame uprights sagging, due to the strains placed thereon, the shell or drum being thus held in alinement with the fixed

shaft 2 under all working conditions, and by reason of its free rotation on the said shaft there is no tendency of the same to bind, although its sustaining shaft may get 5 out of true longitudinal alinement.

On the outer end of the hub 4 is loosely mounted the disk or circumferential flange 16 therefor, and between the same and the inner circumferential flange 5 of such hub 10 the disk web of the drive member is securely held by means of the transversely disposed connecting bolts 4². This web is composed of a plurality of layers *a*, *b*, *c*, consisting each of segmental wooden pieces, which are 15 built up to form a solid web, the outermost layer *a* of the series of layers being extended a slight distance beyond the periphery of the layers *b* and *c*. The periphery of the layers *b* and *c* are embraced or encircled by 20 a metallic rim 16', which rim is provided with and carries a sprocket-ring 17, which constitutes a drive ring for the calf wheel. To the web thus formed is united a built up 25 brake surface for the drive member of the calf wheel, the same consisting of a series of segmental pieces 17' which are placed together and united to the web of the drive disk by means of the transverse bolts 18, which extend through the segmental pieces 30 17', and the metallic rim 16'. The brake surface thus formed is provided with a metallic brake band or rim 18', which is engaged by any suitable form of brake mechanism, not shown, and onto said band or rim 35 falls the frictional wear.

The built up drive disk is driven by means of a sprocket chain, not shown, working over the sprocket ring 17, which chain is usually driven from a sprocket pinion on a crank 40 shaft within the frame of the oil derrick. However, rotation may be imparted to the drive disk by any suitable form of power mechanism.

By the use of the described drive disk as

applied to a calf wheel, the driving power 45 is more effectually applied to the said wheel than by the means at present employed, and the action of the brake mechanism being applied directly to the periphery of the said disk, a quicker response is secured than by 50 the employment of a brake surface independent of the drive disk, besides a compact form of a drive and brake disk is provided for the calf wheel.

Having thus described the invention what 55 is claimed as new and desired to be protected by Letters Patent is—

In a calf wheel for oil derricks, the combination with a fixed sustaining shaft, a shell loosely mounted thereon for free rotation, and bearing hubs loose on said shaft and united to the ends of said rotatable shell, and collars adjustable on the sustaining shaft for preventing longitudinal movement of the hubs and shell relative to said shaft, 60 annular flanges projecting from said hubs, a drive disk secured to said last mentioned flange, said drive disk being composed of a plurality of segments arranged in layers, each layer being arranged transversely to an 65 adjacent layer to form a solid mass, a drive ring encircling the periphery of said drive disk, an annular brake member constructed of a plurality of annular segments and of a diameter greater than said drive disk, a 70 metallic brake band surrounding said brake member, and means for uniting said brake member to said drive member and for retaining said drive ring in position on said 75 disk.

In testimony whereof I have signed my name to this specification in the presence of two subscribing witnesses.

JAMES T. HALL.
